UNITED STATES PATENT OFFICE.

JOHN NICHOL AND JOSEPH WILLSON, OF BLENHEIM, CANADA.

LADDER.

SPECIFICATION forming part of Letters Patent No. 619,334, dated February 14, 1899.

Application filed September 10, 1898. Serial No. 690,708. (No model.)

To all whom it may concern:

Be it known that we, JOHN NICHOL and JOSEPH WILLSON, subjects of the Queen of Great Britain, residing at Blenheim, in the county of Kent and Dominion of Canada, have invented certain new and useful Improvements in Ladders, of which the following is a specification, reference being had therein to the accompanying drawings.

- 10 The invention consists in the peculiar construction, arrangement, and combination of parts, and particularly in the following details: the construction of the combined guide, locking-dog, and stop, the means employed for engaging and disengaging the lower ends of the ladder-sections and for pivoting the upper ends of said sections, the means of securing in position a second extension-section, and the construction of the ladder-rounds.
- 15 In the drawings, Figure 1 is an elevation of our device as arranged for an extension-ladder. Fig. 2 is a perspective view of it as arranged for a step-ladder. Fig. 3 is a sectional elevation of the upper ends of the ladder-sections in the position shown in Fig. 2. Fig. 4 is an enlarged section on line xx , Fig. 1. Fig. 5 is a cross-section on line yy , Fig. 1. Fig. 6 is a cross-section on line zz , Fig. 1. Fig. 7 is a perspective view of one side of the main 25 ladder-section at its lower end. Fig. 8 is a section on line ww , Fig. 1, with the sections separated.
- 20 A is the main ladder comprising sides b and rounds c , and B is the extension-section, provided with sides a and similar rounds.

35 C is a rock-shaft extending across the upper end of the main section. D are rock-arms secured to this shaft in recesses E formed in the inner faces of the side bars b of the 30 main ladder. These rock-arms are provided at their outer ends with laterally-projecting lugs d , which extend over the side bars of the extension-section B and form guides therefor. The side bars b of the main ladder are 40 provided on their inner faces with the longitudinal slots e , with which slides F on the lower end of the side bars a engage. These slides are preferably in the form of angle-brackets secured to the outer sides of the 45 section B, and to engage and disengage them from the slots e entering-slots f are provided

opening into said slots e and through which said slides may pass.

In the upper ends of the side bars of the ladder B are formed semicircular bearing-faces g , which engage over the hubs of the rock-arms D, carried by the rock-shaft C. This forms the pivotal connection between the ladder-sections when they are used as a step-ladder and constitutes a smooth bearing, which allows the sections to be readily moved away from and to each other, as desired.

G is a rock-arm secured to the rock-shaft C, which has attached to its free end the pulley H.

I is a hoisting-cord secured to the lower round h of the section B and passing over the pulley H and down again to the lower end of the main ladder.

With the parts thus constructed to use the device as an extension-ladder the slides F are engaged with the slots e . The extension-section B is normally held in any position of adjustment by the arms D, which are in a slightly-inclined position and act as friction-dogs, holding the section from sliding down. To raise or lower the ladder, the operator draws upon the cord I, which will first rock the shaft C sufficiently to raise the arms D from their inclined position, freeing the extension-section B, which may then be lifted or dropped, as desired.

To use the device as a step-ladder, the section B is lowered to register the slides F with the entering-slots f and to engage the notches g with their bearings on the rock-shaft C. The lower end of the section B may then be swung out until it strikes against the lugs d on the rock-arms D, which act as stops.

It will be noticed that the rock-arms D perform the triple function of friction-dogs, guides, and stops, while their hubs form the pivotal bearings for the extension-section B of the ladder.

The rounds of the ladder are preferably constructed, as shown in Fig. 6 of the drawings, by having end sections i of reduced diameter, with the beveled shoulder k between said sections and the larger portion. The side bars of the ladder are provided with apertures corresponding in diameter with the sections i

and countersunk to fit the beveled shoulders *k*. With this construction the rounds are much stronger than where formed with a square shoulder and are less liable to come 5 loose from the side bars than where the ends are tapering.

- When a greater extension is desired, we preferably provide an extra section *J*. This is secured to the upper end of the section *B* by 10 having notches *K* at the lower ends of the side bars, adapted to engage with the upper round *L* of the section *B*, the latter being preferably flattened at its sides. The upper ends of the side bars *a* are also notched at *M* to engage 15 with pins *N*, projecting from the sides of the section *J*. If desired, instead the rock-shaft *C* may be provided with an operating connection *O*, extending down one side of the main ladder.
- 20 What we claim as our invention is—
1. In an extension-ladder the combination with the main and the extension sections thereof, of a rock-shaft extending across the upper end of said main section, rock-arms thereon having laterally-projecting lugs en- 25

gaging with the side bars of the extension-section to form guides and locking-dogs therefor, a hoisting-cord for said extension-section, and a connection to said rock-shaft over which said cord passes, substantially as described. 30

2. In an extension-ladder, the combination with the main section, of an extension-section of less width than the main section, adapted to be arranged intermediate the sides of the latter section and to swing outwardly from 35 said latter section, and a stop mechanism for limiting the upward movement of the extension-section, and comprising the rock-shaft *C* extending across the upper end of the main section, and the rock-arms *D* thereon having 40 the laterally-projecting lugs *d* adapted to engage with the sides of the extension-section.

In testimony whereof we affix our signatures in presence of two witnesses.

JOHN NICHOL.

JOSEPH ^{his} X WILLSON.
